UNITED STATES PATENT OFFICE.

REUBEN E. BECHTOLD, OF FORT WAYNE, INDIANA, ASSIGNOR TO S. F. BOWSER & CO., INC., OF FORT WAYNE, INDIANA, A CORPORATION OF INDIANA.

CONTROLLING MECHANISM FOR PUMPS.

1,164,699.

Specification of Letters Patent. Patented Dec. 21, 1915.

Application filed July 1, 1912. Serial No. 706,850.

To all whom it may concern:

Be it known that I, REUBEN E. BECHTOLD, a citizen of the United States, residing at Fort Wayne, in the county of Allen and State of Indiana, have invented certain new and useful Improvements in Controlling Mechanism for Pumps, of which the following is a specification.

This invention relates to controlling mechanism for hand pumps of a type in which the hand lever is adapted to be rotated continuously in one direction to effect the operation of the pump, and from which the liquid discharged during each revolution is a specified amount.

The principal object of the invention is to provide means whereby the pump may be stopped at the completion of any revolution of the hand lever, or at the starting point, without any attention of the operator, or may be operated continuously at the will of the operator.

Another object of the invention is to provide means to control the operation of the pump through the grip of the hand lever.

For the attainment of these ends and the accomplishment of other new and useful objects, as will appear, my invention consists of the features of novelty in the construction, combination and arrangement of the several parts generally shown in the accompanying drawings and described in the specification, but more particularly pointed out in the appended claims.

In the drawings, Figure 1 is a side elevation with parts broken away for clearness, of a reciprocating pump to which my controlling mechanism may be applied; Fig. 2 is a detail view of a locking device for the pump controlling mechanism; Fig. 3 is a detail view of registering indicators located upon relatively movable parts of the pump and the hand lever; Fig. 4 is a side elevation of the pump controlling mechanism showing the parts in dotted outline; Fig. 4^a is a detail sectional view on the line 4^a—4^a of Fig. 4; Fig. 5 is a sectional plan view of the controlling mechanism as applied to a pump of the type illustrated in Fig. 1; Fig. 6 is a detail sectional view taken on the line 6—6, of Fig. 5; Fig. 7 is an enlarged detail view of the grip on the hand lever showing its operating connection more clearly.

In pumping different amounts of liquid

from a pump in which the crank handle is turned continuously in one direction, it is not always convenient to watch an indicator or meter to determine the actual amount of liquid discharged, and in the pumps of this class usually employed, it is customary to provide a stop which must be either set in position to engage the operating mechanism at a specific or predetermined point, or to permit the operation of the pump continuously.

The present invention is designed to provide means for either stopping the operating lever at a predetermined point, or for allowing the lever to be rotated continuously. This mechanism is also controlled by the operation of the hand grip of the operating lever so that the same hand which operates the pump may also be employed to control the operation of the pump in any way desired. To release the operating lever the grip must first be pressed longitudinally and rotated to move the operating rod, which will remain in either position, and the operating lever may then be continuously rotated; but if during any revolution the operator wishes to stop the pump at the completion of a full stroke, a simple operation of the hand grip will effect the stop without any further attention of the operator. Any amount less than that pumped by a complete rotation of the hand lever may be pumped by a partial rotation thereof, and indicating means are provided at any desired points to indicate any desired amount.

Referring now more particularly to the drawings, and in the present exemplification of the invention, the controlling mechanism is shown as applied to a pump of the type having a plurality of separate single acting pistons reciprocable in a vertical direction, and provided with means to cause the power stroke of the separate pumps to overlap whereby a continuous flow and pressure of liquid pumped may be obtained by the use of two single acting pump elements.

In Fig. 1 the reference number 10 designates generally the pump casing, and the supporting means for the various portions of the pump comprising pump cylinders 11, pistons 12, a piston rod 13, a connecting link 14, a crank shaft 15, and the stroke varying members 16 which are suitably

mounted upon the adjustable eccentric pivot pin 17. As these parts constitute no part of the present invention, a detailed description of their construction and operation is not deemed necessary.

As shown in Fig. 5, the crank shaft 15 is suitably mounted at one end in the pump casing 10, and at the other end by means of a removable casing plate 18 which is suitably secured to the pump casing 10 by means of the screws 19 or other suitable fastening devices. This casing plate or casing 18 provides a bearing for one end of the crank shaft which is designated by the reference numeral 20, and it is to this end of the crank-shaft that the controlling mechanism will be considered to be applied.

By reference now more particularly to Figs. 5 to 7 inclusive, it will be seen that the end 20 of the crank shaft is provided with a ratchet member 21 which is preferably secured to the shaft by means of a key 22. At the side of the end portion 20 and preferably disposed so as to bear against the inner side of the casing member 18, is a flange 23, and freely mounted between the flange and the ratchet member 21 upon the end of the shaft 20, is a collar 24. Surrounding the ratchet member 21 for a portion of its length, is a sleeve 25 preferably hardened on the inner surface thereof, and surrounding the collar 24, and overlapping the ratchet member 21, is another sleeve 26. This sleeve 26 may be formed integrally within the casing 18, but is preferably of a removable construction and is secured to the casing in any desired or suitable manner. The other sleeve 25 is secured to the hand lever or operating member 27 for the mechanism, which will be hereinafter described. The ratchet member 21 is provided with a plurality of longitudinally extending recesses or grooves 28 in which there are disposed the clutching rollers 29. The bottom 45 of the grooves 28 are inclined so that in the direction of rotation, the rollers 29 if pressed outwardly, will engage the sleeve 25, thereby engaging the operating member 27 with the crank shaft. To effect the outward movement of the clutching rollers 29, coil springs 30 are provided and are disposed in an extension of the groove 28 so that they tend to press the rollers outwardly. From this it is evident that in one direction of rotation, the rollers 29 will engage the operating member 27 with the crank shaft, and in the other direction of rotation, the operating member will be free to rotate.

Disposed beneath the sleeve 26 and located in the ratchet member 21 are other clutching rollers 31, preferably similar in construction and operation to those already described. From this it will be seen that the rotation of the operating member 27 in one direction will effect the engagement thereof

with the crank shaft 20, and in the reverse rotation of the operating member it will be free of the shaft with means provided in connection with the ratchet member 21 to prevent the reverse rotation of the crank- 70 shaft.

The casing plate 18 is preferably formed with an extending portion 32 and the operating member is preferably formed with an extending portion 33, substantially the 75 same outside diameter as the extending portion 32 and having a portion projecting beneath the extending portion 32 of the casing member. Connected to the operating member 27 and preferably formed integrally therewith, is an operating lever 34 at the end of which there is mounted upon a pivot pin 35, a hand grip 36. The extending portions 32 and 33, preferably form an annular chamber surrounding the end of the crank 80 shaft, and pivotally mounted in connection with the operating member 27 are the engagement dogs 37. The inner edge of the extending portion 32 of the casing member 18 is preferably formed with shoulders 38 90 suitably spaced apart and disposed in opposite directions, and the dogs 37 are provided with springs 39 which tend to press them normally into engagement with the shoulders. These shoulders and dogs are so disposed that both dogs are in engagement with both of the shoulders at the same time so that a relative movement of the operating member 27 and a pump casing is prevented. One of the dogs 37, however, is located adjacent the inner end of the lever 34 and is provided with a projection in the form of a stirrup or pocket 40. Extending longitudinally or substantially parallel with the hand lever 34, and disposed between projecting webs 34^a at the sides of the lever 34, is an operating rod 41, one end of which is seated in the pocket 40 of the dog 37, and the other end of which is slightly bent and positioned at one side of a collar 42 which 100 is rotatably mounted upon the pivot pin 35. This collar 42 is disposed between the grip 36 and the lever 34, and a coil spring 43 is preferably provided to press the collar and the grip normally apart. The collar 110 and the grip are provided, however, with interengaging teeth 44 by means of which the collar may be rotated by the grip when the grip is pressed to overcome the spring 43 and against the collar 42 so that the said teeth are interengaging. The normal position of the rod 41 is such as to allow the dog 37 to be in engagement with its shoulder 38, as shown in Fig. 4, and at this time, the other end of the rod 41 will be in engagement with the inside of the web 34^a at one side of the lever as shown by this figure. When it is desired to free the dog 120 from its engagement with the shoulder, it is necessary only to press the hand grip 36 125 130

in the collar 32 and to rotate the hand grip slightly to raise the rod, and to raise the dog from its engagement, the rod being held in raised position by the engagement of its bent portion with the inside of the web 34^a at the other side of the operating lever 34.

From this description it is evident that a slight movement only of the hand grip is necessary to effect the control of the operating mechanism. Furthermore, the control may be effected by means of one hand. With the construction shown and described, it is also evident that the operating lever cannot be rotated in a reverse direction further than the predetermined point. It is understood, of course, that shoulders may also be provided at other points about the members 18 so that the operating lever may be stopped at any position and prevented from reverse rotation from any position.

In order to indicate when a predetermined amount less than that pumped by an entire rotation of the pump lever, indicators 45 may be provided on the adjacent extending portions 32 and 33 (see Fig. 3) which will indicate any desired amount. From this it will be evident that a fractional part of the amount pumped upon a complete stroke, may be discharged and the lever 34 returned to its starting or a previously determined point in the reverse direction. The operating member 27 may be secured to the pump in any desired or suitable manner, such for example as by means of a plate 46 disposed on the outside of the end of the shaft to which it is secured by means of a screw 47, the operating member 27 being free to rotate without engaging the plate 46.

In order to lock the operating member in any desired position, the casing member 18 is preferably provided with a projection 48 (see Figs. 2 and 4) which is formed with an abutment 49 in which projection a locking member 50 is pivotally mounted. This locking member 50 is provided with a recess 51 which is adapted to seat a coil spring 52 which presses normally against the abutment 49 tending thereby to press the locking member outwardly. The locking member 50 is also provided with an extension 53 adjacent the pivotal mounting in the projection 48 which is adapted to bear against the abutment 49 when the locking member 50 is rotated a certain amount about its pivotal mounting. The object of this extension is to prevent the locking member from swinging too far outwardly from the member to which it is pivotally connected. The pump casing member 18 is provided with an opening 54, and the operating member 27 is provided with an opening 55, preferably in the extending portion 33 and so disposed with respect to the opening 54, that the two openings register when the operating member 27 is rotated to a predetermined position.

It is to be understood that the portions 32 and 33 overlap so that a single projection may be inserted in the openings which register to lock the two members in any desired position. It is also to be understood that there may be any desired number of locking positions, it being necessary only to provide a series or a number of perforations or openings in the projecting portion of the operating member 27.

Projecting from the casing member 18 adjacent the opening 54 therein and preferably on the side opposite the pivotally mounted locking member 50, is a catch 56, and suitably arranged in the member 50 is a lock 57 which has a latch 58 operated by a key and adapted to engage the catch 56. The lock 57 may be of any desired or suitable construction, it being necessary only to provide means to move the latch 58 to disengage it from the catch 56 when it is desired to release the locking member 50. The locking member 50 is provided with a projection 59 which may be and preferably is formed integrally with the locking member and which is adapted to be inserted through the openings 54 and 55. It is evident that when the projection 59 is inserted through the openings the relative movement of the operating member 27 with respect to the casing member 18 is prevented. The locking member 50 is also provided with a shield portion 60 at the outer end thereof adapted to inclose the latch 58 and the catch 56 when the locking member is in locked position, thereby preventing any one from tampering with the engagement of the latch with the catch. As soon as the latch is released from the catch 56, the spring 52 is operative to press the locking member outwardly so that the projection 59 is free of engagement with the operating member 27 so that it is free to be rotated.

In order to register the total amount of fluid pumped, a registering device 61 (see Fig. 5) may be provided, which is secured to the pump casing 10 and which has positive engagement with the crank shaft 15 by means of the gears 62 and 63. As this registering device constitutes no part of the present invention, it is deemed sufficient to say that it may be of any desired type which is suitable to register the amount pumped by the continuous operation of the pump in a single direction.

From the foregoing description it is evident that the starting and stopping of the pump at any predetermined point is at all times under the control of the operator, and that he may without interfering with the continuous operation of the pump, effect the automatic stopping thereof at a predetermined point during any revolution of the operating member. It is also evident that the control of the operating member may be effected by the hand which effects the pump-

ing operation, and without any other means so that the other hand may be free to do anything else which is necessary, such for example, as to hold or to steady the vessel 5 which is used to contain the fluid pumped.

While I have thus described the preferred construction, combination, arrangement and application of my invention, it is evident that others skilled in the art to which this 10 appertains, may make various changes therein without departing from the spirit and scope of the invention.

What I claim is:

1. The combination of a pump comprising 15 a handled operating lever, and a locking device operated from the pump operating lever by the rotation of the handle.

2. The combination of a pump comprising 20 a handled operating lever, and means in connection with the handle of the lever operated by the rotation of the handle to lock and unlock the lever at a predetermined point.

3. The combination with a pump having 25 an operating lever, of movable means directly connected to the lever to lock and unlock it at a predetermined point, and a rotary handle to operate the means by its rotation.

30 4. The combination with a pump having a rotatable operating lever, of a rotatable handle connected to the lever, and means controlled by the rotation of the handle to lock and unlock the lever at a predetermined point.

5. The combination with a pump having 35 an operating lever, of means to lock the lever at a predetermined point, and a rotatable handle in connection with the lever to release the lever from the locking means by its rotation.

6. The combination with a pump having 40 a rotatable operating lever, of means to lock the lever at a predetermined point against rotation in either direction, and a rotatable handle in connection with the lever to release the locking means by its rotation for permitting the rotation of the lever in one direction.

50 7. The combination with a pump having a rotatable operating lever, of means to lock the lever at a predetermined point in either direction of rotation, and means in connection with the lever to release the locking means and permit the rotation of the lever.

8. The combination with a pump having 55 a rotatable operating lever, of means to lock the lever at a predetermined point in either direction of rotation, and means in connection with the lever to release it, the said means being effective to permit the rotation of the lever in one direction only to the predetermined point, and in the other direction past the said point.

45 9. The combination with a pump having

a rotatable operating lever, of means to stop the lever at a predetermined point, and means in connection with the lever and operable at will to disengage the stop means and to prevent its operation.

10. The combination with a pump, of an operating hand lever therefor rotatable in one direction to effect the pumping action, means to prevent the reverse rotation past a certain point, stopping means to lock the lever with the pump at a predetermined point, and means operated at will from the outer end of the hand lever to release the lever and to prevent the engagement by the stopping means.

11. The combination with a pump, of an operating hand lever therefor rotatable in one direction to effect the pumping action, stopping means to lock the lever at a predetermined point, an independently rotatable grip mounted on the lever, and means in connection therewith to release the lever.

12. The combination with a pump, of an operating hand lever therefor rotatable in one direction to effect the pumping action, stopping means to lock the lever at a predetermined point, an independently rotatable grip mounted on the lever, and a rod operated by the grip to release and to prevent the locking of the lever.

13. The combination with a pump, of an operating hand lever therefor rotatable in one direction to effect the pumping action, stopping means to lock the lever at a predetermined point, an independently rotatable grip mounted on the lever, and a rod positioned by the lever and operated by the grip to release and to prevent the engagement of the lever.

14. The combination with a pump, of an operating hand lever therefor rotatable in one direction to effect the pumping action, stopping means to lock the lever at a predetermined point, an independently rotatable grip mounted on the lever, and a rod parallel with and partially inclosed by the lever, and operated by the grip to release and to prevent the locking of the lever.

15. The combination with a pump, of an operating lever therefor rotatable to effect the pumping action, means to lock the lever at a predetermined point, a rotatable collar mounted upon the lever, a rod having one end pivoted in the collar and operative to release the said locking means, and a hand grip mounted on the lever movable to engage the collar to operate the said rod.

16. The combination with a pump, of an operating lever therefor rotatable to effect the pumping action, means to lock the lever at a predetermined point, a rotatable collar mounted upon the lever, a rod having one end pivoted in the collar and operative to release the said locking means, a hand grip mounted on the lever movable to engage the

collar to operate the said rod, and means acting normally to oppose the engagement of the grip with the collar.

17. The combination with a pump, of an operating lever therefor rotatable to effect the pumping action, means to lock the lever at a predetermined point, a rotatable collar mounted upon the lever, a rod having one end pivoted in the collar and operative to release the said locking means, a hand grip mounted on the lever movable to engage the collar to operate the said rod, the grip and collar being formed with interengaging means, and a spring interposed therebetween to oppose the engagement of the grip with the collar.

18. The combination of a pump, of a rotatable operating lever therefor, a dog pivotally mounted upon the lever, a casing plate having a shoulder to engage the dog, means to press the dog into such engagement, a rotatable hand grip at the free end of the lever, and means in connection with the grip to disengage the dog from the shoulder and to hold it in disengaged position.

19. The combination with a pump having a crank shaft, of a rotatable operating lever therefor, a dog having a projecting pocket portion pivotally mounted upon the lever, a casing plate having a shoulder to engage the dog, a coil spring to press the dog normally into engagement with said shoulder, a rotatable collar mounted on the crank shaft, a hand grip at the end of the lever, the grip and collar being provided with interengaging means, and a rod pivoted at one end in the collar and engaging in the said pocket of the dog at the other, the rotation of the grip, when engaging the collar, being effective to move the rod to disengage the dog from the said shoulder.

20. The combination with a pump, of a rotatable operating lever connected to the pump crank shaft, a shouldered casing plate, dogs pivotally mounted on the operating lever adapted to engage the casing plate and to hold the lever in a predetermined position, and means in connection with the lever to release one of the dogs from such engagement.

21. The combination with a pump having an operating shaft, of a rotatable operating lever, means to engage the lever with the pump shaft to rotate the shaft in one direction only, and means to directly engage the shaft only for preventing its rotation in the reverse direction.

22. The combination with a pump having a rotatable operating shaft, of a lever therefor, means to lock the lever and the shaft when said lever is rotating in one direction, the lever being released when rotated in the other direction, and means to prevent the said shaft from rotating in the said other direction.

23. The combination with a pump having an operating shaft rotatable in the pump casing, of a lever therefor, means to lock the shaft with the lever when it is rotated, in one direction and to permit the free rotation thereof in the other direction, a shouldered casing plate, dogs pivotally mounted on the lever to engage the casing plate and to hold the lever at a predetermined point, means in connection with the lever to release one of the dogs to permit the rotation thereof in one direction, and means to prevent the rotation of the operating shaft in the said other direction.

24. The combination with a pump having a rotatable operating shaft, of a lever therefor having a hub, a fixed casing plate, a member keyed to the shaft and disposed within the hub of the lever, clutching rollers mounted in said member to engage the lever when rotated in one direction, and means to prevent the rotation of the shaft when the lever is rotated in the other direction.

25. The combination with a pump having an operating shaft rotatable in the pump casing, of a lever therefor having a hub, a fixed casing plate, a member keyed to the shaft and disposed within the hub of the lever, clutching rollers mounted in said member to engage the lever when rotated in one direction, and other clutching rollers in said member and operative to engage the casing plate to prevent the reverse rotation of the said operating shaft when the lever is rotated in the reverse direction.

26. The combination with a pump having a plurality of separate cylinders, a crank shaft for reciprocating the pump pistons in the cylinders, an operating lever for said shaft, means to lock the lever to the shaft in one direction of rotation, a stop device in connection with the lever to prevent the rotation of the lever past a certain point in the other direction and to lock the lever in a predetermined position, means in connection with the lever to release the lever to permit its rotation in an operative direction and to prevent the engagement thereof when the lever is rotating in the operative direction, and clutching means to prevent the rotation of the crank shaft in the said other direction.

27. The combination with a pump having reciprocable plungers and a shaft to operate them in succession, of an operating lever, means to lock the lever to shaft in one direction of rotation and to permit the lever to rotate freely in the reverse direction, means to limit the movement of the lever in the reverse direction, and means to prevent the reverse rotation of the pump shaft.

28. The combination with a pump, of a casing plate therefor having an extending portion, an operating lever therefor having a flange substantially the same outside di-

ameter as the said extending casing, means to lock the lever to the shaft to rotate it in one direction and to permit the free rotation of the shaft to a predetermined point 5 in the other direction, the pump being adapted to pump a predetermined amount upon each rotation in the operative direction, and indicators positioned upon the adjacent positions of the casing and the flange 10 to point out when an amount less than that of a complete cycle of the operating lever

stroke has been pumped, the lever being then returnable to the said predetermined point.

In testimony whereof I have signed my name to this specification, in the presence of 15 two subscribing witnesses, on this 26th day of June A. D. 1912.

REUBEN E. BECHTOLD.
